UNITED STATES PATENT OFFICE.

FLORENCE E. BRYANT, OF ADAMS, MASSACHUSETTS.

DESIGN FOR A BASIN-STAND.

SPECIFICATION forming part of Design No. 30,424, dated March 28, 1899.

Application filed March 3, 1899. Serial No. 707,671. Term of patent 7 years.

To all whom it may concern.

Be it known that I, FLORENCE E. BRYANT, a citizen of the United States, residing at Adams, in the county of Berkshire and State of Massachusetts, have invented and produced a new and useful Design for a Basin-Stand, of which the following is a full, clear, and exact description, reference being had to the drawings forming part of this specification, in which—

Figure 1 is a perspective view of a basin-stand, showing my new design. Fig. 2 is a plan view of the same, and Fig. 3 is a side view thereof.

As shown in the drawings, the leading or material feature of my design comprises the slender rod-like body made to conform to a circle A in plan view, but substantially rectilinear as seen from the side, such annulus being formed with the narrow U-shaped bends B, projecting uniformly beneath the same. The ends of said rod-like body or wire

A are caused to extend diametrically across the annulus, said portions or ends C being substantially parallel and rectilinear. The entire structure is tinned or nickel-plated to increase its neatness of appearance.

While my entire design comprises the annulus A, the U-shaped projections or legs B, and the diametrical ends or chords C, the essential portion of my design consists of the annulus and the legs.

Having described my invention, what I claim as new, and desire to secure by Letters Patent, is—

The design for a basin-stand, as herein shown and described.

In testimony that I claim the foregoing invention I have hereunto set my hand this 28th day of February, 1899.

FLORENCE E. BRYANT.
